BEDSTEAD CARRIAGE

John D. Martin, Cleveland, Ohio

Application April 9, 1957, Serial No. 651,607

5 Claims. (Cl. 5—328)

This invention relates generally to bedstead carriages, but has reference more particularly to means for facilitating movement of conventional bedsteads.

A conventional bedstead generally comprises a headboard, a footboard, and side rails rigidly supported by the headboard and footboard, the side rails being usually provided at their ends with hook-like elements which engage pins in the headboard and footboard, thereby removably securing the side rails to the headboard and footboard.

In most cases, the side rails are provided on their in-board surfaces with cleats upon which the ends of bed slats are supported, these bed slats, in turn, supporting the spring and mattress of the bed.

The housewife, when attempting to move the bed, for purposes of cleaning the carpet or floor under the bed or for other reasons, usually pulls the footboard away from the wall, but the combined weight of the bedstead, spring and mattress is so great, that in many instances, the hook-like elements in the side rails are dislodged from their anchorage in the side rails. Even when casters are mounted in the legs which support the headboard and footboard, for the purpose of facilitating movement of the bedstead and its load, the overall weight is still sufficient to result in dislodgment of the hook-like elements, under the circumstances stated.

The present invention has, as its primary object, the provision of means for facilitating movement of a conventional bedstead and its load, while eliminating or minimizing the possibility of the hook-like elements from becoming dislodged from the side rails during such movement.

Another object of the invention is to provide means of the character described, in the form of a conventional or modified Hollywood bed or frame.

A further object of the invention is to provide means of the character described, including a novel form of bracket, which may be quickly and easily attached to the side rails of a conventional bedstead, with a minimum of tools and labor.

A still further object of the invention is to provide a conventional bedstead, in which the use of cleats for supporting the spring and mattress is dispensed with, and in which the hook-like elements of the side rails are arranged or disposed in a manner which is different from that in which they are conventionally disposed or arranged.

In the accompanying drawings forming a part of this specification, and in which like numerals are employed to designate like parts throughout the same,

Fig. 1 is a perspective view, showing the invention, with a portion thereof broken away to more clearly show certain features;

Fig. 2 is a fragmentary side elevational view;

Fig. 3 is a fragmentary cross-sectional view, taken on the line 3—3 of Fig. 1;

Fig. 4 is a fragmentary cross-sectional view, taken on the line 4—4 of Fig. 1;

2

Fig. 5 is a perspective view of one of the brackets, and Fig. 6 is a cross-sectional view, taken on the line 6—6 of Fig. 5.

Referring more particularly to the drawings, reference numerals 1 and 2 designate the headboard and footboard respectively of a conventional bedstead, and 3 and 4 the side rails of the bedstead. The headboard and footboard are usually provided with legs 5.

In this case, the side rails 3 and 4 are not provided with cleats for supporting any bed slats, since, as will be presently described, the side rails are not designed to support the spring and mattress of the bed.

The side rails 3 and 4 have anchored in the ends thereof, vertically-spaced pairs of metallic hook-like elements 6, which, as shown in Fig. 4, are engaged with pins 7 in the headboard and footboard, for the purpose of rigidly securing the headboard and footboard to the side rails. Since, as will appear hereinafter, the entire bedstead is designed to be supported in spaced relation to the carpet or floor of the bedroom, the hook-like elements 6, in this case, instead of extending downwardly, as in conventional bedsteads, are extended upwardly, so as to eliminate any possibility of the headboard and footboard from slipping off the hook-like elements 6.

25 The bedstead carriage, in this case, is shown as a conventional Hollywood bed, comprising a rectangular frame consisting of transversely-spaced longitudinally extending angles 8 and 9, and longitudinally-spaced transversely extending angles 10 and 11, the latter being provided with legs 12 supported on casters 13, for facilitating rolling movement of the Hollywood bed. Where box springs are utilized, the spring may be supported directly on the horizontal flanges 14 of the angles 8 and 9, and the mattress supported on the spring. Where springs other than box springs are used, bed slats may be supported on the flanges 14 and the spring and mattress supported on the bed slats.

30 For the purpose of mounting the bedstead on the carriage, I have provided four sheet-metal brackets, each 40 having a rectangular body portion 15, which is secured to the inner surface of each side rail, adjacent the end thereof, as by screws 16. Each bracket is also provided with a rectangular hook-like flange 17, formed integrally with the body portion 15 and extending downwardly 45 from the upper edge of the body portion, the flange 17 being generally parallel with the body portion 15. These flanges are engaged over the vertical flanges 18 of the angles 8 and 9, and in order to increase the frictional engagement of these brackets with the vertical flanges 18, 50 the inner surfaces of the brackets are provided with embossments or projections 19. To facilitate placement of the flanges 17 over the flanges 18, the flanges 17 may have their lower portions inturned, as at 20.

In securing the brackets to the side rails 3 and 4, they are so placed, that when secured in proper position, the bedstead will be elevated above the carpet or floor of the bedroom, in the manner shown in Fig. 2.

55 It will be apparent from the foregoing description that the bedstead is supported by the carriage entirely off the floor, and may thus be moved as a unit. By supporting the spring and mattress on the carriage, rather than on the bedstead, the bedstead is relieved of the load of the spring and mattress, so that the unit (bedstead) may be easily moved, for the purpose of cleaning under the bed 60 or for other purposes, and the possibility of the hook-like elements becoming dislodged from the side rails is eliminated or minimized.

65 The brackets may be easily and quickly attached to the side rails of a conventional bedstead, with a minimum of 70 tools and labor.

Moreover, the use of cleats on the side rails for supporting the spring and mattress is avoided, and the hook-

like elements 6 are, as shown in Fig. 4, disposed in a manner such that the headboard and footboard cannot slip off the side rails.

It is to be understood that the form of my invention, herewith shown and described, is to be taken as a preferred example of the same, and that various changes in the shape, size and arrangement of parts of my invention may be made without departing from the spirit of the invention, or the scope of the subjoined claims.

Having thus described my invention, I claim:

1. In combination, a bedstead comprising a headboard, footboard and side rails, brackets secured to the inner surfaces of said side rails and provided with flanges extending downwardly from the upper edges of the brackets, a caster-supported frame for supporting said bedstead in spaced relation to the floor of a room, said frame comprising angle members having vertical flanges in parallel spaced relation to said side rails, said bracket flanges engaged with said angle member flanges, whereby said bedstead is supported by the upper edges of the angle member flanges.

2. The combination, as defined in claim 1, in which the angle member flanges are snugly disposed between the secured portions of the brackets and the flanges of the brackets.

3. In combination, a bedstead comprising a headboard, footboard and side rails, brackets secured to the inner surfaces of said side rails, a caster-supported frame

for supporting said bedstead in spaced relation to the floor of a room, said brackets provided with hook-like flanges, and said frame comprising angle members having vertical flanges over which said hook-like flanges are engaged.

4. The combination, as defined in claim 3, in which said brackets have rectangular body portions screwed to the inner surfaces of the side rails.

5. The combination, as defined in claim 4, in which said angle members are provided with horizontal flanges upon which the spring and mattress of the bed are adapted to be supported.
